UNITED STATES PATENT OFFICE.

ALFRED B. LAWSON, OF IRENE, VIRGINIA.

CATTLE-GUARD.

SPECIFICATION forming part of Letters Patent No. 752,294, dated February 16, 1904.

Application filed December 7, 1903. Serial No. 184,089. (No model.)

To all whom it may concern:

Be it known that I, ALFRED B. LAWSON, a citizen of the United States, residing at Irene, in the county of Loudoun and State of Virginia, have invented new and useful Improvements in Cattle-Guards, of which the following is a specification.

The main object of my invention is to provide a cattle-guard which shall be an improvement over existing devices of that nature, and in designing means to carry out that object I have had in mind the desirability of simplicity in construction, durability, reliability, and safety in operation, for all these characteristics are essential in order that a cattle-guard of the type to be described may successfully meet the requirements of actual use upon the railroads.

The means which I have employed to satisfy these requirements will now be described in detail, reference being had to the accompanying drawings, in which—

Figure 1 is a perspective view of my improved cattle-guard as it appears in actual use on a railroad. Fig. 2 is a longitudinal sectional view taken on the line 2 2 of Fig. 1. Fig. 3 is a transverse sectional view through the road-bed and rails, showing the guard in end elevation.

In the figures, 1 indicates the rails, and 2 the ties, of an ordinary railroad-track. At the place where the cattle-guard is to be located a tie is omitted or removed and a trench is dug between the two remaining adjacent ties, as indicated at 3. The depth of this trench is governed by the distance between said ties. Thus assuming that distance to be about three feet the trench may be from one foot to one foot and a half in depth, the reason for which will be apparent from the description which follows of the operation of my device. Midway between the two remaining ties 2 2 and immediately beneath the rails 1 1 two posts 4 4 are erected, cut away at the top to receive the flanges of the rails, as indicated at 5. In practice these posts will be securely held at the bottom of the trench by inserting them in holes dug therein and tamping the earth solidly around them, and this, taken in connection with the construction by which said post

fit snugly on the flanges of the rails, enables them to serve the double function of standards for the cattle-guard proper in the manner to be described and of supports for the rails at the place where the tie has been removed. Running transversely of the track and journaled in apertures in the posts 4 4 a short distance below the tops of said posts is a shaft 6, extending laterally the full width of the trench, which is dug entirely across the road-bed, so as to cause the guard to effectively prevent the straying of cattle onto the track.

A metal plate 7 is securely clamped to the shaft 6, as by the brackets indicated at 8, and extends practically from rail to rail and from tie to tie, so as to substantially cover the trench, and similar plates 9 9 of the necessary width are securely clamped in the same way to the end portions of the shafts 6 outside of the rails. Of course, if preferred, the shaft 6 may be held so as not to turn in the posts, and in that case the plates 7 and 9 would be rotatively mounted on said shaft, which modification would be the equivalent of the construction shown, in which modifications and changes may be made—such, for example, as providing bushings for the shaft 6 in the posts 4 4—without in any way departing from the principle of operation of my invention.

Each of the plates 7 and 9 is provided at its ends adjacent to the ties 2 with upwardly-projecting flanges 10, which extend up approximately to the level of the bottom of the rails or to that of the top of the ties, although, if preferred, said flanges may extend somewhat higher.

The lower ends of the posts 4 4 are preferably braced by a cross-piece 11, which serves also for the attachment of one end of each of two tension-springs 12 12, the other ends of which are secured to the under side of the plate 7 near its outer ends, as shown. Should the cross-piece 11 not be used, however, the springs 12, of which four may be employed, if desired, would be attached directly to the posts 4 4, with their upper ends near the sides of the plate 7, or any other arrangement of springs and attaching means may be used, the only requisite being that the springs act

to normally hold the plates 7 and 9 in the horizontal plane and to return them to that position after displacement. Where the plates are rotatively mounted on the shaft each must 5 obviously be provided with springs.

The operation of the device will now be apparent. When an animal attempts to pass onto the track, if it steps over the flange 10 onto either the plate 7 or one of the plates 9 10 the plate will immediately be depressed, which will cause the animal to draw back in fear, the flange 10 acting to prevent its feet from slipping off the plate into the trench and the springs 12 limiting the downward movement 15 of that end of the plate upon which the animal has stepped and acting to return the plates to the horizontal as soon as the weight of the animal is removed. The upraised opposite end of the plate effectually bars the further 20 advance of the animal should it attempt to continue.

It will thus be seen that I have devised a cattle-guard which is extremely simple to construct and install and which will prove a perfectly reliable means to prevent the passage 25 of cattle onto the track of a railroad and at the same time act without danger of injury to an animal attempting such passage.

As indicated above, various changes and 30 modifications may be made in the details of construction and assemblage of the device without materially changing its nature and method of operation or departing from the principle of my invention, which is defined in 35 the following claims.

What I claim is—

1. A cattle-guard for railroads, comprising a centrally-pivoted plate provided with upwardly-extending flanges at its outer ends and 40 means to normally maintain said plate horizontal.

2. A cattle-guard for railroads, comprising plates pivotally supported at their centers between and outside of the rails and provided 45 with upwardly-extending flanges at their outer ends, and yielding means to normally maintain said plates horizontal.

3. A cattle-guard for railroads, comprising a plate extending between the rails and pivotally supported at its center, a plate at the outside of each rail pivotally supported at its center, upwardly-extending flanges on the ends of said plates, and springs to normally maintain said plates horizontal.

55 4. A cattle-guard for railroads, comprising a post beneath each rail taking the place of

an ordinary tie, a shaft passing transversely through said posts, plates centrally mounted to swing around the axis of said shaft as a center, and springs to normally maintain said 60 plates horizontal.

5. A cattle-guard for railroads, comprising two posts oppositely located in a trench extending transversely of the road-bed, the tops of said posts being constructed to fit on the 65 flanges of the rails, a shaft passing transversely through said posts a short distance beneath the rails, plates centrally mounted to swing about the axis of said shaft as a center and springs to normally maintain said plates horizontal. 70

6. A cattle-guard for railroads, comprising two posts oppositely located in a trench extending transversely of the road-bed, the tops of said posts being constructed to fit on the 75 flange of the rails, a shaft passing transversely through said posts a short distance beneath the rails, plates centrally mounted to swing about the axis of said shaft as a center, said plates being provided with upwardly-extending 80 flanges at their outer ends and springs to normally maintain said plates horizontal.

7. A cattle-guard for railroads, comprising two posts securely held in the center of a trench extending transversely of the road-bed, 85 said posts acting to support the rails in the place of a tie, a shaft journaled transversely in said posts a short distance below the rails, a plate centrally secured to said shaft between the rails, a plate centrally secured to said shaft on the outer side of each rail, and yielding means to normally maintain said plates horizontal. 90

8. A cattle-guard for railroads, comprising two posts securely held in the center of a 95 trench extending transversely of the road-bed, said posts being shaped to fit the flanges of the rails and to support the rails in the place of a tie, a shaft journaled in said posts and carrying centrally mounted thereon a plate 100 between the rails and a plate on the outside of each rail, each of said plates being provided on its opposite ends with upwardly-extending flanges, and yielding means to normally maintain said plates horizontal. 105

In testimony whereof I have signed my name to this specification in the presence of two subscribing witnesses.

ALFRED B. LAWSON.
